CHICK BOX

William B. Stouffer, Mount Morris, Ill.

Application September 4, 1934, Serial No. 742,521

17 Claims.

(Cl. 229—6)

This invention relates to a new and improved box for shipping or carrying live chicks.

Incubation is now done mainly in large hatcheries from which the young chicks are distributed to the farms where they are to be raised. A large percentage of these chicks go to farms not far distant from the hatchery and are transported usually by the farmer himself by automobile or truck. There is no necessity, therefore, of providing expensive shipping containers made of heavy corrugated fibre board throughout on such short hauls. It is the principal object of my invention to provide a chick box of cheaper construction, one which requires no stapling and which uses lighter and hence cheaper materials, the box being made partly of paper sheet material and partly of paper board material, instead of being made throughout of paper board. While designed so as to be inexpensive enough for local delivery use, the box is nevertheless strong enough for use in shipping by express and parcel post for considerable distances, especially when reenforced for that purpose as hereinafter described.

Another object is to provide a box in which the partitions extend diagonally in crisscross relation so that triangular compartments instead of four-cornered compartments are formed, and there is less tendency for crowding in corners, and hence less danger of smothering. This arrangement of the partitions is particularly advantageous in a box constructed, as herein disclosed, using light sheet material for the sides, because the partitions extend into the corners and thus support the sides at their ends, lending the desired strength and rigidity. It also makes possible a strong construction without stapling, the partitions being simply slid into place.

Another object is to so construct the box to provide for better ventilation, and, at the same time, better insulation, especially for the floor and sides, so that chilling is avoided.

The invention is hereinafter described by reference to the accompanying drawings, in which—

Figure 1 is a perspective of a chick box made in accordance with my invention;

Fig. 2 is a perspective of the box with the cover removed;

Fig. 3 is a perspective view looking at the bottom of the box;

Fig. 4 is a section on the line 4—4 of Fig. 1;

Fig. 5 is a somewhat similar section showing a modification;

Fig. 6 is a plan view of a box with the cover

removed, showing the addition of reenforcing pieces in the sides, and

Fig. 7 is a sectional detail on the line 7—7 of Fig. 6.

Similar reference numerals are applied to corresponding parts throughout the views.

Referring to Figs. 1 to 4, the chick box of my invention has the square body or frame 8 thereof made of kraft paper, or any other similar tough and fairly stiff wrapping paper, or for that matter any similar light sheet material. This frame is formed like an ordinary paper bag to provide sides 9 and a bottom 10, the material being tucked in and folded and glued, as indicated at 11 in Fig. 3, to form the bottom, similarly as in a bag. 15 A square floor-piece 12 of corrugated fibre board is placed on the bottom 10 inside this bag-like frame, and it has marginal upwardly projecting flanges 13 which have abutment with the inside of the side walls 9. The latter are folded inwardly to provide inner side walls 9' spaced from the outer side walls, reaching down far enough to overlap the upper edges of the flanges 13, as appears in Fig. 4, thus giving a good finish to the interior of the box. This mode of assembling also 20 results in the provision of the air space 14 between the inner and outer side walls, as clearly appears in Fig. 4, thus affording substantially the same insulation with this sheet material construction as is ordinarily provided with corrugated fibre board construction. The double thickness side walls also make for the requisite strength and rigidity. The present construction also results in a greatly increased thickness of material in the bottom 10 30 added to the thickness of material in the floor 12, resulting in a much warmer box than where fibre board of single thickness is used alone in the bottom. The square form of the box is furthermore pretty well defined with this much of the construction alone. Two partitions 15 and 16 of corrugated fibre board are slotted vertically at the middle, one from the top down and the other from the bottom up, as at 17, to permit interfitting the partitions at the point of intersection, as 35 shown in Fig. 2, and are entered in the frame 8 reaching diagonally between the corners of the box. In this way, four triangular compartments 18 of equal size are provided instead of the usual four-cornered compartments. Each compartment in a full sized box—20" by 20"—will accommodate twenty-five chicks, and there is less opportunity for these chicks to crowd into corners and be smothered, there being only three corners as compared with the customary four in 40

each compartment. The criss-crossed partitions fitting in the corners naturally provide good support for the sides 9—9' and provide cross bracing such that the box is much stronger than where the corners are left unbraced. It is this feature which in a large part accounts for the strength and rigidity of the present box, despite the fact that light sheet material is employed for the sides and bottom instead of paper board. Furthermore, this strength is built into the box without necessitating any stapling, the partitions being simply slid into place at the corners. If desired, the ends of the partitions may be first dipped in glue so that, when they are entered, they will soon thereafter be united firmly to the corners, and thus make for even greater strength and rigidity. The saving in labor cost in setting up the box from knockdown condition as compared with a stapled box can easily be appreciated, and the parts required in the construction of this box are of such simple form that less labor is required in the making thereof, so that a double saving in the cost of production results. The saving in cost derived through the use of sheet paper material or the like, as distinguished from paper board material for such a large part of the box, is, however, one of the most important savings. A further saving is contemplated by making the floor piece 12 of lighter and cheaper material than the partitions 15 and 16, and by making the cover 19 of still lighter and cheaper material.

The cover 19, which is of paper board material, is large enough to overhang the sides of the box about a half inch, as indicated in Figs. 1 and 4, so as to be sure to form a good closure for all of the compartments 18. A small diagonally extending slot 20 is provided in the cover at the center to permit projection therethrough of a lug 21 provided on the upper edge of the partition 15 at the middle. A nail or other fastener 22 can be inserted in the lug 21 to hold the cover in place, as shown in Figure 1. Additional means for locating and holding the cover is afforded by tabs 23 bent downwardly from the cover into frictional engagement with the sides of the partitions 15 and 16. The sticks 24, glued or otherwise suitably secured on top of the cover at the corners, provide support for another box in spaced relation to the cover when two or more are placed in a stack or are secured together for shipment as a single package. The holes 25 formed where the tabs 23 are bent in, as just described, serve for ventilation, along with other holes 26 punched through the cover, and, when two or more boxes are stacked together and separated, as just described, with the sticks 24, there is, of course, no danger of these holes being closed. Other holes 27 are punched through the sides 9—9' and still other holes 28 through the partitions 15 and 16 for further ventilation of the compartments 18 in the box. The fact that the cover 19 projects from the sides of the box a half inch or so, as above mentioned, insures against the covering up of the holes 27 by other boxes or packages.

Referring now to Figs. 6 and 7, the sides of the box may, if desired, be reenforced by the insertion of pieces 29 of paper board material, fitting at the ends at the angles between the side walls of the box and the ends of the partitions 15—16. These pieces will, of course, not only add strength and rigidity, but also greatly increase the insulation in the side walls, making these walls about twice as resistant to heat losses as where a single thickness of paper board is em-

ployed, there being the additional insulation space 14, previously described. With such a construction, holes 27' are provided in the pieces 29 in register with the holes 27 for ventilation. While a box constructed along the lines of Figs. 5 1 to 4 is particularly suited for local delivery due to its low cost, it should be understood that it is not intended solely for such use but may also be used in long distance shipping. However, the slight additional expense involved for the 10 reenforcements 29 may be considered worth while in chick boxes for express and parcel post shipments going considerable distances.

In Fig. 5, a modification of the structure of Fig. 4 is shown in which there are outer and inner side walls 9a and 9b, respectively, provided in a frame 8', and only the outer wall 9a is provided with ventilation holes 27a, the inner wall 9b being ordinarily spaced sufficiently at its lower edge from the inside of the flange 13 to 20 allow air to enter between the walls, as indicated by the arrows. In other words, with this construction, there is indirect ventilation and less likelihood of the chicks being chilled by sudden gusts of air; the inner wall 9b will serve as a 25 baffle or shield.

It is believed the foregoing description conveys a good understanding of the objects and advantages of my invention. The appended claims have been drawn with a view to covering 30 all legitimate modifications and adaptations.

I claim:

1. A box of the class described comprising a bag-like body of relatively light, foldable sheet material providing a bottom and side walls, a 35 separate rectangular floor-piece of heavier, stiffer board material resting on said bottom and holding the side walls out so as to partially define a rectangular box structure, criss-crossed vertical partitions of stiff board material fitting in the 40 said structure over the floor-piece so that the ends of the partitions enter the corners and support said side walls, and a cover for the box.

2. A box of the class described comprising a bag-like body of relatively light, foldable sheet material providing a bottom and side walls, a separate rectangular floor-piece of heavier, stiffer board material resting on said bottom and holding the side walls out so as to partially define a rectangular box structure, the side walls 50 being folded in to provide side walls of double thickness, criss-crossed vertical partitions of stiff board material fitting in the said structure over the floor-piece so that the ends of the partitions enter the corners and support said side walls, 55 and a cover for the box.

3. A box of the class described comprising a bag-like body of relatively light, foldable sheet material providing a bottom and side walls, a separate rectangular floor-piece of heavier, 60 stiffer board material resting on said bottom and holding the side walls out so as to partially define a rectangular box structure, the side walls being folded in to provide side walls of double thickness, the floor-piece having marginal upwardly projecting flanges entered between the inner and outer plies of said side walls to space the same for the purpose described, criss-crossed vertical partitions of stiff board material fitting in the said structure over the floor-piece so that the ends of the partitions enter the corners and support said side walls, and a cover for the box. 65

4. A box as set forth in claim 2, wherein the outer ply of said side walls has ventilation openings provided therein, and the inside ply serves 75

as a shield covering said openings but allowing circulation of air downwardly between the plies and under the inner ply into the box.

5. A box of the class described comprising a bag-like body of relatively light, foldable sheet material providing a bottom and side walls, a separate rectangular floor-piece of heavier, stiffer board material resting on said bottom and holding the side walls out so as to partially define a rectangular box structure, criss-crossed vertical partitions of stiff board material fitting in the said structure over the floor-piece so that the ends of the partitions enter the corners and support said side walls, supplemental pieces of board material disposed along the inside of said side walls reaching from corner to corner and serving to further strengthen the side walls of the structure, and a cover for the box.

10. A box of the class described comprising a bag-like body of relatively light, foldable sheet material providing a bottom and side walls, a separate rectangular floor-piece of heavier, stiffer board material resting on said bottom and holding the side walls out so as to partially define a rectangular box structure, the side walls being folded in to provide side walls of double thickness, criss-crossed vertical partitions of stiff board material fitting in the said structure over the floor-piece so that the ends of the partitions enter the corners and support said side walls, supplemental pieces of board material disposed along the inside of said side walls reaching from corner to corner and serving to further strengthen the side walls of the structure, and a cover for the box.

15. A box of the class described comprising a bag-like body of relatively light, foldable sheet material providing a bottom and side walls, a separate rectangular floor-piece of heavier, stiffer board material resting on said bottom and holding the side walls out so as to partially define a rectangular box structure, the side walls being folded in to provide side walls of double thickness, the floor-piece having marginal upwardly projecting flanges entered between the inner and outer plies of said side walls to space the same for the purpose described, criss-crossed vertical partitions of stiff board material fitting in the said structure over the floor-piece so that the ends of the partitions enter the corners and support said side walls, supplemental pieces of board material disposed along the inside of said side walls reaching from corner to corner and serving to further strengthen the side walls of the structure, and a cover from the box.

20. In a box of the class described, the combination of a bag-like rectangular container having bottom, sides, and removable cover, vertical criss-crossed partitions having their ends entered frictionally in the corners of said container so as to support the sides and maintain the rectangular shape of said container.

25. A chick box comprising a stiff rectangular floor-piece, a rectangular cover of similar material, criss-crossed vertical partitions disposed diagonally with respect to the top of said floor-piece under said cover, and enclosing side walls of lighter sheet material supported along the bottom by the marginal edges of the floor-piece and along the ends by the ends of the partitions.

30. A chick box comprising a stiff rectangular floor-piece, a rectangular cover of similar ma-

terial, criss-crossed vertical partitions disposed diagonally with respect to the top of said floor-piece under said cover, and a rectangular body part of lighter sheet material having bottom and side walls, the floor-piece being removably entered in said body on said bottom, and said partitions being removably entered on top of said floor with the ends of the partitions engaging the inside of the side walls at the corners.

35. A box as set forth in claim 10 wherein said sheet material is foldable, and the side walls are folded in so as to provide spaced inner and outer side walls.

40. A box as set forth in claim 10 wherein said sheet material is foldable, and the side walls are folded in so as to provide spaced inner and outer side walls, and wherein the floor-piece has marginal upwardly projecting flanges, the inside of which is overlapped by the lower edges of the inner side walls.

45. A box as set forth in claim 10 wherein said sheet material is foldable, and the side walls are folded in so as to provide spaced inner and outer side walls, and wherein the outer walls have openings provided therein above the lower edges of the inner side walls.

50. A chick box comprising a stiff rectangular floor-piece, a rectangular cover of similar material, criss-crossed vertical partitions disposed diagonally with respect to the top of said floor-piece under said cover, and enclosing side walls of lighter sheet material, the same being folded so as to provide spaced inner and outer side walls.

55. In a box of the character described comprising a rectangular container having bottom and side walls, partitions dividing the inclosed space into compartments, one of said partitions having an upwardly extending lug at the middle thereof, a cover for said container having an opening to receive said lug, the lug projecting through said opening and adapted to receive a transverse fastener for holding the cover in place, and means on top of the cover at the corners, reaching to an elevation above the plane of the top of said lug, for spacing said box from other articles placed thereon.

60. In a box of the character described comprising a rectangular container having bottom and side walls, partitions dividing the inclosed space into compartments, one of said partitions having an upwardly extending lug at the middle thereof, a cover for said container having an opening to receive said lug, the lug projecting through said opening and adapted to receive a transverse fastener for holding the cover in place, and bifurcated lugs on said cover bendable downwardly to straddle the upper edges of said partitions to frictionally hold the cover in place.

65. A chick box comprising a rectangular floor-piece of board material, a rectangular cover of similar material, partitions of similar material vertically disposed over said floor-piece beneath the cover, and enclosing side walls of lighter sheet material for the floor-piece and partitions supported along the bottom by the marginal edges of the floor-piece and along the ends by the ends of the partitions, the floor-piece having its marginal edges flanged upwardly for reenforcement thereof, whereby to keep the bottom of the box straight, the flanges having engagement with the inside of the side walls.

70. WILLIAM B. STOUFFER.
